UNITED STATES PATENT OFFICE.

JAMES E. KIMBLE, OF VICKSBURG, MICHIGAN.

OIL FEED OR CHARGE DELIVERING DEVICE.

No. 892,267.

Specification of Letters Patent.

Patented June 30, 1908.

Application filed August 22, 1906. Serial No. 331,653.

To all whom it may concern:

Be it known that I, JAMES E. KIMBLE, a citizen of the United States, residing at Vicksburg, in the county of Kalamazoo and State of Michigan, have invented certain new and useful Improvements in Oil Feed or Charge Delivering Devices, of which the following is a specification.

This invention relates to improvements in oil feed or charge delivering devices.

My improved oil feed or charge delivering device is particularly designed for use as a lubricator, although it is very desirable for use as a liquid hydrocarbon feed device for explosion engines or the like.

The objects of this invention are, first, to provide an improved feed device of the class described adapted to deliver a fixed amount at each charge. Second, to provide an improved feed device of the class described, which is positive in its action. Third, to provide an improved feed device of the class described which is very simple in construction and very durable in use.

Further objects, and objects relating to structural details, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing forming a part of this specification, in which—

Figure 1 is a side elevation of a structure embodying the features of my invention. Fig. 2 is an end elevation looking from the left of Fig. 1. Fig. 3 is an enlarged horizontal detail section, taken on a line corresponding to line 3 3 of Figs. 1 and 4. Fig. 4 is a detail vertical section taken on a line corresponding to line 4 4 of Fig. 3, showing structural details. Fig. 5 is an enlarged vertical section taken on a line corresponding to line 5 5 of Fig. 3, showing structural details. Fig. 6 is a detail view of the feed cylinder removed from the cylinder chamber. Fig. 7 is a similar detail view of a modified construction having two charge pockets. Fig. 8 is a similar detail view of another modification having two charge pockets. Fig. 9 is a detail view showing a modification of the driving connection. Fig. 10 is a side elevation show-

ing another modification of the driving connection.

In the drawing the sectional views are taken looking in the direction of the little arrows at the ends of the section lines, and similar letters of reference refer to similar parts throughout the several views.

Referring to the drawing, A is the oil receptacle or reservoir, which is preferably provided with the base pieces A' by means of which it is secured in position. The reservoir is provided with a suitable cover, as A''. In the bottom of the receptacle is a cylinder chamber a, the same being preferably formed integral therewith. This cylinder chamber 70 extends transversely through the reservoir and is adapted to receive the revoluble feed cylinder. This feed cylinder preferably consists of a shaft B on which the sleeve-like member B' is arranged and secured, preferably by a pin, as b, arranged therethrough. On the outer end of the shaft B is mounted a ratchet segment C'. A sleeve-like member B'' is movably mounted upon the shaft B. This sleeve is of the same diameter as the 80 sleeve B', both being adapted to revolvably fit within the cylinder chamber. The adjacent ends of the sleeves B' B'' are cut away to form the extensions b' b'' respectively, the extension of one member fitting into the cut 85 away portion of the other, the parts of the members being shouldered together as clearly appears in the drawings and coat to form the charge pocket, see Figs. 6, 7 and 8.

On the outer end of the sleeve B'' a 90 ratchet segment C is mounted. These segments are somewhat greater than half an arc and are arranged oppositely so that they overlap, as appears in Figs. 1 and 3. A bearing, as E, is provided for the cylinder, 95 the bearing preferably being threaded into the end of the cylinder chamber, as is illustrated. The cylinder members B' B'' are held in contact by the coiled spring e. The coiled spring e is held in position by the 100 threaded cylinder chamber cap E'. (See Fig. 3.)

The segment C is preferably provided with an inwardly projecting hub c on which the rock lever D is mounted. On this rock 105 lever D is the pawl d, arranged to act upon the segments C and C'. The pawl is provided with a spring d' for holding it in engagement. The rock lever D is actuated by the rod D' or other suitable means.

With the parts in the position shown in the drawing, the actuation of the rock lever D acts upon the segment C', revolving the shaft B until the charge pocket, which 5 then opens into the discharge passage G', is closed, at the same time opening the charge pocket on the opposite side into the inlet passage G. The continued movement revolves the cylinder B' until the position of 10 the pockets is reversed. The pawl then engages the segment C of the member B'', moving it upon the shaft B until it in turn engages the member B', which movement forces the charge into the discharge passage 15 G' and opens the opposite pocket into the inlet passage G the pawl thus alternately acting upon the segments to alternately actuate the members B' and B''.

In order to insure the movement of the 20 parts in proper relation to each other, I provide the friction blocks F', one of which engages the member B' and the other the member B''. These friction blocks are arranged in suitable holes bored into the wall 25 of the cylinder chamber, and bear against the sides of the members, as clearly appears in Fig. 3. The blocks are held yieldingly in position by the coiled springs f. The tension of these springs f is regulated by the 30 threaded blocks F which close the outer ends of the holes.

The discharge passage G' is connected by the tube G'' or otherwise to the part to be lubricated, or to which the oil is to be delivered. It is evident that my improved 35 feed device delivers effectively against pressure. As the charge pockets open in the inlet passage G, thereby creating a vacuum, they are positively filled at each stroke, so 40 that an even charge is insured, and this is true although the lubricant may be quite heavy or thick.

Where it is desired to deliver two or more charges at the same time, the ends of the 45 members B' B'' may be formed as is illustrated in Fig. 7, in which two pockets are shown. A further modification is shown in Fig. 8, where a sleeve-like member B''' is interposed between the members B' B''. The ends of this sleeve are formed to coact 50 with the members B' B'' in the same manner that they coact with each other in the structure of Fig. 1. In such a structure the charge pockets close successively, as will be 55 readily understood.

While I prefer to drive the charge cylinder by the rock lever shown in the preferred construction, the same might be driven by means of the pulley c' on the shaft c, on 60 which is a pinion c' arranged to mesh with the segments C and C'.

In the modified form of the driving connection shown in Fig. 10, the gear H is provided with trips h for the double pawl I, so 65 that the device is first actuated in one di-

rection and then in the opposite direction, thereby opening the pocket in the inlet passages and closing it in the outlet. The pawl I is supported on suitable pivoted bearings i on the rock lever D. The pawl 70 is held against one or the other stops on the rock lever by means of spring K which is mounted on a pin j. This pin j is pivotally supported by the stud J. Other means of alternately imparting movement to the 75 members of the feed cylinder will readily appear to those skilled in the art to which this invention relates. The friction blocks also serve the purpose of holding the cylinder in position, so that accurate fitting is not 80 required and also the necessity for packing removed. I thus accomplish in a simple manner the opening of the charge pockets in the reservoir and the closing of the same in the discharge passage. As before stated, 85 when the pockets are opened a vacuum is created so that they are positively filled.

While my improved feed device is particularly adapted for use as a lubricator, it is desirable for use in other relations, as is 90 heretofore stated. I have illustrated and described my improved feed device in detail in the form preferred by me, although I am aware that it is capable of considerable variation in structural details without departing from my invention.

Having thus described my invention, what I claim as new and desire to secure by Letters Patent, is:

1. The combination of a cylindrical chamber having an inlet and a discharge passage; a cylinder arranged within said chamber, consisting of a central shaft, a sleeve-like member fixed upon said shaft, and a sleeve-like member movably mounted on said shaft, 100 said members being shouldered together to form a charge pocket; a pair of ratchet segments secured upon said shaft and movably mounted cylinder member, arranged to overlap; a rock lever; a pawl carried thereby, 105 arranged to engage said segments; a spring arranged to hold said cylinder members together; friction blocks arranged to bear against said cylinder members; springs for applying tension thereto; and means for 110 regulating the tension of said springs, for the purpose specified.

2. The combination of a cylindrical chamber having an inlet and a discharge passage; a cylinder arranged within said chamber, 115 consisting of a central shaft, a sleeve-like member fixed upon said shaft, and a sleeve-like member movably mounted on said shaft, said members being shouldered together to form a charge pocket; a pair of ratchet segments secured upon said shaft and movably mounted cylinder member, arranged to overlap; a rock lever; a pawl carried thereby, 120 arranged to engage said segments; friction blocks arranged to bear against said cylinder 125 members; and means for regulating the tension of said springs, for the purpose specified.

members; springs for applying tension thereto; and means for regulating the tension of said springs, for the purpose specified.

3. The combination of a cylindrical chamber having an inlet and a discharge passage; a cylinder arranged within said chamber, consisting of a central shaft, a sleeve-like member fixed upon said shaft, and a sleeve-like member movably mounted on said shaft, 10 said members being shouldered together to form a charge pocket; a pair of ratchet segments secured upon said shaft and movably mounted cylinder member, arranged to overlap; a rock lever; a pawl carried thereby, 15 arranged to engage said segments; a spring arranged to hold said cylinder members together; and friction blocks arranged to bear against said cylinder members, for the purpose specified.

20 4. The combination of a cylindrical chamber having an inlet and a discharge passage; a cylinder arranged within said chamber, consisting of a central shaft, a sleeve-like member fixed upon said shaft, and a sleeve-like member movably mounted on said shaft, 25 said members being shouldered together to form a charge pocket; a pair of ratchet segments secured upon said shaft and movably mounted cylinder member, arranged to overlap; a rock lever; a pawl carried thereby, 30 arranged to engage said segments; and friction blocks arranged to bear against said cylinder members, for the purpose specified.

5. The combination of a cylindrical chamber having an inlet and a discharge passage; 35 a cylinder arranged within said chamber, consisting of a central shaft, a sleeve-like member fixed upon said shaft, and a sleeve-like member movably mounted on said shaft, 40 said members being shouldered together to form a charge pocket; a pair of ratchet segments secured upon said shaft and movably mounted cylinder member, arranged to overlap; a rock lever; a pawl carried thereby, 45 arranged to engage said segments; and a spring arranged to hold said cylinder members together, for the purpose specified.

6. The combination of a cylindrical chamber having an inlet and a discharge passage; 50 a cylinder arranged within said chamber, consisting of a central shaft, a sleeve-like member fixed upon said shaft, and a sleeve-like member movably mounted on said shaft, 55 said members being shouldered together to form a charge pocket; a pair of ratchet segments secured upon said shaft and movably mounted cylinder member, arranged to overlap; a rock lever; and a pawl carried thereby, 60 arranged to engage said segments, for the purpose specified.

7. The combination of a cylindrical chamber having an inlet and a discharge passage; 65 a cylinder arranged within said chamber, consisting of a central shaft, a sleeve-like member fixed upon said shaft, and a sleeve-

like member movably mounted on said shaft, 70 said members being shouldered together to form a charge pocket; a pair of segments secured upon said shaft and movably mounted cylinder member, arranged to overlap; a 75 spring arranged to hold said cylinder members together; friction blocks arranged to bear against said cylinder members; springs for applying tension thereto; and means for regulating the tension of said springs, for the 80 purpose specified.

8. The combination of a cylindrical chamber having an inlet and a discharge passage; 85 a cylinder arranged within said chamber, consisting of a central shaft, a sleeve-like member fixed upon said shaft, and a sleeve-like member movably mounted on said shaft, 90 said members being shouldered together to form a charge pocket; a pair of segments secured upon said shaft and movably mounted cylinder member, arranged to overlap; friction blocks arranged to bear against said cylinder members; springs for applying tension thereto; and means for regulating the tension of said springs, for the 95 purpose specified.

9. The combination of a cylindrical chamber having an inlet and a discharge passage; 100 a cylinder arranged within said chamber, consisting of a central shaft, a sleeve-like member fixed upon said shaft, and a sleeve-like member movably mounted on said shaft, 105 said members being shouldered together to form a charge pocket; a pair of segments secured upon said shaft and movably mounted cylinder member, arranged to overlap; a 110 spring arranged to hold said cylinder members together; and friction blocks arranged to bear against said cylinder members, for the 115 purpose specified.

10. The combination of a cylindrical chamber having an inlet and a discharge passage; 120 a cylinder arranged within said chamber, consisting of a central shaft, a sleeve-like member fixed upon said shaft, and a sleeve-like member movably mounted on said shaft, 125 said members being shouldered together to form a charge pocket; a pair of segments secured upon said shaft and movably mounted cylinder member, arranged to overlap; and friction blocks arranged to bear against said 130 cylinder members, for the purpose specified.

11. The combination of a cylindrical chamber having an inlet and a discharge passage; 135 a cylinder arranged within said chamber, consisting of a central shaft, a sleeve-like member fixed upon said shaft, and a sleeve-like member movably mounted on said shaft, 140 said members being shouldered together to form a charge pocket; a pair of segments secured upon said shaft and movably mounted cylinder member, arranged to overlap; and a 145 spring arranged to hold said cylinder members together, for the purpose specified.

12. The combination of a cylindrical chamber having an inlet and a discharge passage; 150

- 5 a cylinder arranged within said chamber, consisting of a central shaft, a sleeve-like member fixed upon said shaft, and a sleeve-like member movably mounted on said shaft, 50 said members being shouldered together to form a charge pocket; and a pair of segments secured upon said shaft and movably mounted cylinder member, arranged to overlap, for the purpose specified.

10 13. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; a pawl carried thereby arranged to engage said segments; a spring arranged to hold said members together; friction blocks arranged to bear against said members; springs for applying tension thereto; and means for regulating the tension of said springs, for the purpose specified. 75

15 14. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; a pawl carried thereby arranged to engage said segments; a spring arranged to hold said members together; friction blocks arranged to bear against said members; springs for applying tension thereto; and means for regulating the tension of said springs, for the purpose specified. 80

20 15. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; a pawl carried thereby arranged to engage said segments; a spring arranged to hold said members together; friction blocks arranged to bear against said members; springs for applying tension thereto; and means for regulating the tension of said springs, for the purpose specified. 85

25 16. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; a pawl carried thereby arranged to engage said segments; friction blocks arranged to bear against said members; springs for applying tension thereto; and means for regulating the tension of said springs, for the purpose specified. 90

30 17. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; a pawl carried thereby arranged to engage said segments; friction blocks arranged to bear against said members; springs for applying tension thereto; and means for regulating the tension of said springs, for the purpose specified. 95

35 18. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; friction blocks arranged to bear against said members; springs for applying tension thereto; and means for regulating the tension of said springs, for the purpose specified. 100

40 19. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a spring arranged to hold said members together; and friction blocks arranged to bear against said members, for the purpose specified. 105

45 20. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; and friction blocks arranged to bear against said members, for the purpose specified. 110

50 21. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; a pawl carried thereby arranged to engage said segments; and a spring arranged to hold said members together, for the purpose specified. 115

55 22. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; and a pawl carried thereby arranged to engage said segments, for the purpose specified. 120

60 23. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; and a pawl carried thereby arranged to engage said segments, for the purpose specified. 125

65 24. The combination of a cylindrical chamber having an inlet passage and a discharge passage; a cylindrical charge pocket member; a cylindrical charge pocket member arranged to coact therewith and movable relatively thereto; a pair of segments arranged to overlap each other, connected to said charge pocket members; a rock lever; and a pawl carried thereby arranged to engage said segments, for the purpose specified. 130

- chamber having an inlet passage and a discharge passage; a cylindrical charge pocket member; a cylindrical charge pocket member arranged to coact therewith and movable 5 relatively thereto; means for revolving said members arranged to act thereon alternately; and friction blocks arranged to bear against said members, for the purpose specified.
- 10 24. The combination of a cylindrical chamber having an inlet passage and a discharge passage; a cylindrical charge pocket member; a cylindrical charge pocket member arranged to coact therewith and movable 15 relatively thereto; and means for revolving said members arranged to act thereon alternately, for the purpose specified.

25. The combination of a chamber having an inlet passage and a discharge passage; a pair of revoluble members coacting to form 20 a charge pocket; and means for revolving said members arranged to act upon the same alternately, whereby said charge pocket is opened in said inlet passage and closed in said discharge passage, for the purpose 25 specified.

In witness whereof, I have hereunto set my hand and seal in the presence of two witnesses.
